[57] **CLAIM**

The ornamental design for a winch housing cover, substantially as shown.

DESCRIPTION

FIG. 1 is an isometric view taken from above and looking toward the front and one side of a winch housing cover showing my new design;

FIG. 2 is a side elevational view thereof;

FIG. 3 is a side elevational view thereof opposite to that shown in FIG. 2;

FIG. 4 is a top plan view thereof;

FIG. 5 is a bottom plan view thereof;

FIG. 6 is a front elevational view thereof; and

FIG. 7 is a rear elevational view thereof.

FIG. 1

FIG. 2

FIG. 3

FIG. 4
